UNITED STATES PATENT OFFICE.

WILFRID LUMLEY, OF CONNEAUT, OHIO.

GLOBE HOLDER FOR LIGHTING FIXTURES.

Application filed December 12, 1921. Serial No. 521,677.

To all whom it may concern:

Be it known that I, WILFRID LUMLEY, a citizen of the United States, residing at Conneaut, in the county of Ashtabula and State of Ohio, have invented a certain new and useful Improvement in Globe Holders for Lighting Fixtures, of which the following is a full, clear, and exact description.

This invention relates to a globe holder for a lamp fixture, and has for its chief object to provide a globe holding device capable of being clamped about or released from the neck of a globe, and which at the same time embodies the feature of simplicity as regards the manner of effecting the clamping or releasing of the globe, and which eliminates the necessity for clamping screws.

The holder embodying the present invention is in the form of a split band adapted to encircle the neck of a globe, with provision for drawing the ends together and for permitting the ends to spread apart to effect the globe clamping and releasing respectively.

Further the invention resides in the means for drawing together or allowing the expansion of the ends of the band, this means being preferably embodied in one of the devices utilized to support the globe holder and globe.

Still further the invention resides in a globe holder having part or all the characteristics above referred to, and additionally shaped so as to afford a degree of adjustability to adapt the holder to globes whose necks are of slightly varying diameters.

The invention may be further briefly summarized as consisting in certain novel details of construction, and combinations and arrangements of parts which will be described in the specification and pointed out in the appended claims.

In the accompanying sheet of drawings, Fig. 1 is a side elevation of my improved holder applied to, or in supporting relation to a globe; Fig. 2 is an enlarged plan view of the holder removed from the globe showing the holder in full lines when it is contracted and its ends clamped as when the holder is supporting the globe, and showing by dotted lines the ends released and the holder somewhat expanded to permit the release or removal of the globe; Fig. 3 is a fragmentary perspective view showing how

one of the holder supporting devices may be utilized to hold the ends of the band or holder in globe supporting position; Fig. 4 is a similar view showing the ends released or spread; and Fig. 5 is a perspective view showing a lamp equipped with my invention.

In the accompanying sheet of drawings, 10 represents the globe of a lamp fixture, which globe may have any suitable design or shape and is adapted to envelop a lamp in the customary manner, this fixture being particularly a ceiling fixture wherein the lamp is supported from an upper wall or ceiling somewhat in the manner illustrated in Fig. 5. The globe has the customary reduced neck portion surmounted by a lip or flange, indicated at 10^a. The globe holder consists of a circular band 11 which may be formed of any suitable material, but preferably from metal having some degree of elasticity which will permit the contraction of the band to the position shown by full lines in Fig. 2, and its expansion, as indicated by dotted lines in the same figure.

The band is provided preferably at equally spaced points with a plurality of loops 12 with circular outer portions and parallel inner portions, as shown in Fig. 2. 85 The number of these loops may be varied and will depend upon the number of points at which the holder and globe are to be supported, as by chains, or cords, or links. In this instance the holder is to be supported at three points, and therefore three such loops are provided. The supporting means or devices are designed to be attached to these loops, and as here shown they include endless straps or links 13 which form a permanent part of the holder and pass through openings in the inner portions of the loops as clearly shown in the different figures of the drawing.

One of these loops, designated 12^a is split 100 at a point indicated at 12^b, forming the two ends of the band which are adapted to be drawn together to contract the band and cause it to hold or support the globe, and which are designed to spread apart to permit the band to expand so as to enable the globe to be withdrawn from the holder.

Ordinarily the links 12 or equivalent means stand in vertical position due to the weight of the globe and of the holder, and when the link extending through the parts of the loop 12^a is in this vertical position,

obviously due to the fact that the link is narrow, the ends of the band at the loop 12^a are held together or in the position shown in Fig. 2, in which event the band is contracted or in condition for supporting the globe. On the other hand, when the link associated with the split loop 12^a is turned from vertical position to horizontal position in the manner indicated in Fig. 4, the 10 ends of the band, or the parts of the split loop 12^a can spring apart so as to allow the band to expand.

It will be seen therefore, that the locking of the band in globe supporting position is 15 brought about by one of the links or parts of the holder supporting means, and that when this link is in supporting position it automatically retains or locks the band in its contracted position. It will be seen also, 20 that it is only necessary to allow the link 13 associated with the split loop 12^a to drop to horizontal position as by relieving this link 13 of the weight of the globe that the ends of the holder are automatically released so that the holder can expand.

Additionally another advantage follows from the use of a holder in the form of a split band having the external loops 12 and 12^a, and this lies in the fact that the loops 30 provide a certain amount of excess metal to enable the band to enlarge somewhat to permit it to be used with a globe somewhat larger than the standard size normally intended to be used with the holder, that is to say, should the external diameters of the 35 necks of the globes vary somewhat, or should the bands vary slightly in size, the inwardly extending parallel sides of the loops 12 may expand so as to allow the holder to be 40 clamped about a globe having a relatively large size neck.

The holder and globe may be supported and connected to the lamp in any suitable manner. For example, in Fig. 5, the globe 45 and globe holder form a part of a ceiling lamp designated as a whole by the reference character 14. In this lamp there is a central fixture 15 which contains the lamp proper, the top of this fixture being supported from above by supporting members 16 and the links 13 of the globe holder being connected to the upper part of the fixture by supporting rods or links 17.

It will be seen therefore, that I have provided a globe holder which does not require holding screws, and which at the same time embodies the features of simplicity and utility to a high degree.

I do not desire to be confined to the exact 60 details shown, but aim in my claims to cover all modifications which do not involve a departure from the spirit and scope of my invention in its broadest aspects.

Having described my invention, I claim:

1. A globe holder for a lamp, comprising 65 a split band adapted to be extended about the neck of a globe, said band having end portions adapted to be drawn together or spread apart to permit the band to be contracted or expanded, and an elongated 70 substantially flat endless link slidably and rotatably engaging the end portions of the band whereby when said link is in a position in which it extends lengthwise alongside the band the band is free to expand and 75 when said link is turned to a position at right angles to the plane of the band said band is contracted and held in contracted position.

2. A globe holder comprising a split band 80 adapted to encircle the neck of a globe, a plurality of holder supporting links connected to said band, and supporting members connected to said links, one of said links 85 adjustably engaging the ends of the band adjacent the split and serving to hold said ends relatively close together or to permit them to spread apart, depending upon the position that the link assumes with reference to said band.

3. A globe holder for a lamp fixture comprising a split band having outstanding ends at the point of the split, and a plurality of holder supporting devices connected to the holder, one of said devices engaging said ends of the band to hold the band contracted, said end engaging supporting device being movable with respect to 95 said ends to a position in which it permits the band to expand.

4. A globe holder for a lamp fixture comprising a split band adapted to encircle the neck of a globe to be held, and provided with a plurality of outwardly extending 100 portions, one divided to form the split in the band, and a plurality of holder supporting devices attached to said portions, and one serving to hold the band contracted and to allow it to expand, depending upon the position that it assumes.

5. A holder for the globe of a lamp fixture comprising a band adapted to encircle the neck of a globe to be held, and provided with a plurality of outwardly extending 105 loops, one of the loops being divided into two parts forming a split band, and a plurality of holder supporting links extending through said loops, one of said links serving to hold the two ends or portions of the split or divided loop relatively close together and to permit them to spread apart, depending upon the position that said link assumes with reference to said loop.

In testimony whereof, I hereunto affix my signature.

WILFRID LUMLEY.
